UNITED STATES PATENT OFFICE.

CHARLES HABART, OF CLEVELAND, OHIO, ASSIGNOR TO JOHN HIST, OF CLEVELAND, OHIO.

HINGE.

Application filed November 13, 1922. Serial No. 600,615.

The present invention relates to a spring door hinge, and the object of the invention is to construct a hinge such that the hinge parts may be separated by removal of the pivot pin without disturbing the spring, so that when it is desired to unhang a door which is mounted by the hinges forming this invention, it will only be necessary to remove the pin of each hinge, and the door may be readily removed while leaving the other part of the hinge in position for replacement of the door when desired.

Hinges of this character are particularly useful in the matter of hanging screen doors where it is undesirable to remove the screws from one of the parts of the hinge when it is desired to remove the door.

Reference should be had to the accompanying drawings forming a part of the specification, in which Fig. 1 is an elevation of the hinge; Fig. 2 is an elevation of one part of the hinge; Fig. 3 is an elevation with portions in section of the other part of the hinge; Fig. 4 is an elevation of the pivot pin by which the hinge parts are pivotally secured together; Fig. 5 is an end elevation of the part shown in Fig. 3; Fig. 6 is a transverse section of the part shown in Fig. 3; Fig. 7 is an end elevation of the part shown in Fig. 2.

Referring to the drawings, one of the hinge parts is designated at 1, and the other is designated at 2. The hinge part 1 comprises a flat base portion 3 which has a cut out integral tongue member which is rolled into a substantially cylindrical member 4 having a slot 5 formed therein in substantially the central part, as clearly indicated in Fig. 3. There are also end pieces 6 which are preferably formed by severing and bending up a portion of the blank from which this hinge part is formed. In fact, the construction which has so far been described can be formed as a stamping, and the portion 4 turned into its substantially cylindrical shape, and the end members 6 severed from the blank and bent into the position in which they are shown in Fig. 3.

The portion 4 is so bent that the inner edge of this portion is slightly spaced from the body portion 3. Within the cylindrical portion 4 and between the side or end member 6 there is a resilient member which in

the present instance takes the form of a spring, and preferably there are two springs within this housing or member 4, each spring, such as the spring 7, being a cylindrical helical spring having one end 8 of the spring extending out from the portion 4 and bearing against the member 1, while the opposite end 9 of the same spring will bear against the bottom of the slot 5.

The helical spring 10 with its free ends 11 and 12 is made and mounted in precisely the same fashion as that described. The other member 2 of the hinge has a flat body portion 13 with upturned ears 14 and 15 which are spaced apart and parallel, and these ears are provided with openings, one of which is indicated at 16. The space between the ears 14 and 15 is but slightly greater than the length of the member 4 on the other part of the hinge, so that when the two parts of the hinge are assembled the portion 4 and the end members 6 of the hinge part 1 will extend between the ears 14 and 15, and the holes in the end members 6 will align with the holes in the ears 14 and 15.

It should further be noted that the helical springs 7 and 10 are in line with the holes in the members 6 and 14 and 15, so that when the members are assembled a pin 18 may be passed through the openings just described and through the central portion of the helical springs 7 and 10. In bringing these hinge members 1 and 2 together the free ends 9 and 12 of the springs are above the plate 13 of the hinge part 2.

When the pin has been inserted then the hinge parts are pivotally mounted with respect to each other, and the hinge parts may be moved toward each other as the pivotal pin 18, thereby placing the spring under tension.

In applying the invention one of the hinge parts may be carried by a door frame and the other of the hinge parts carried by the door, there being suitable screw or nail holes provided for this purpose in each of the hinge parts, as indicated at 1^a and 2^a. When the door is opened the hinge parts move relatively about the pivot pin 18, and the spring is compressed so that when the door is released it is moved back to its initial position.

By simply removing the hinge pin of each hinge the hinge parts may be separated

and the spring element is definitely retained in its position, so that when the door is again to be hung the hinge parts are brought into their proper relation, as before described, 5 the pin 18 reinserted in proper position in each of the hinge parts, and the door is ready for operation.

Having described my invention, I claim:—

1. A hinge comprising two members, 10 means for detachably and pivotally connecting said members, and means for yieldingly opposing a relative movement of the members about their pivot from a normal position and for returning the same to normal 15 position comprising a coil spring permanently mounted on one of the members, said spring having one end fixed to the member on which it is mounted and the other end projecting over and bearing against the 20 other hinge member, the hinge member on which the spring is mounted having means for retaining the spring thereon and for limiting the unwinding movement thereof, said means comprising a cylindrical portion 25 fixed on one of the members entirely enclosing the coils of the spring to retain the spring and having a circumferentially extending slot through which the projecting end of the spring extends, said slot permitting 30 movement of the projecting end of the spring upon a relative pivotal movement of the hinge members and so disposed that one end thereof is engaged by the projecting end of the spring when the members are disconnected whereby the spring is retained 35 under normal tension.

2. A hinge comprising two sheet metal members, said sheet metal members each having a base portion and upstanding pivot 40 portions, one of said members having its inner edge portion rolled back upon itself to form a cylindrical portion along its inner edge lying outside the plane of its base portion, said cylindrical portion having a 45 slot in its wall extending circumferentially from substantially the plane of the base portion on the side toward the other hinge member, a coil spring enclosed by and retained within said cylindrical portion, said 50 spring having one end fixed to the hinge member upon which it is mounted and its opposite end projecting through the slot and normally engaging the base of the slot when the members are separated whereby it is 55 retained under tension, and means for detachably pivoting the sections for pivotal movement substantially about the axis of the cylinder, the end of the spring projecting through the slot being engageable with the 60 other hinge member and movable in the slot to yieldingly resist relative pivotal movement of the hinge members in one direction and to return the hinge members to normal position, and said members being separable 65 one from the other or attachable one to the

other without disturbing the spring or releasing the tension thereof.

3. A hinge comprising a member having a body portion and spaced ears upstanding therefrom, said ears having aligned openings, a second member having a body portion and an integral fixed cylindrical portion adapted to be positioned between the ears of the first member to alignment with the openings thereof, said cylindrical portion having a circumferentially extending slot in its wall, a spring enclosed by and retained within said cylindrical portion, said spring having one end secured to the second member and its opposite end projecting through the slot when the members are separated and normally engaging an end of the slot whereby it is retained under normal tension, and a removable pin pivotally connecting the sections, said pin extending through said ears and cylinder and through the spring within the cylinder, the projecting end of said spring engaging with the first mentioned hinge member whereby the spring will be flexed upon movement of said member in one direction about its pivot and will yieldingly resist such pivotal movement, said members being separable one from the other when the hinge pin is removed and adapted to be fitted together to receive the hinge pin without disturbing the spring or releasing the tension thereof.

4. A hinge comprising a sheet metal member having a base portion and an edge integral portion turned outwardly and back upon itself to form a cylindrical portion and ears struck up from the base portion closing the ends of the cylindrical portion, said ears having openings therein, said cylindrical portion having a circumferential slot in the wall thereof extending outwardly from substantially the plane of the base at the outer side of the cylindrical portion, a coil spring mounted within the cylindrical portion, said spring having one end secured to said member and its opposite end projecting through the slot and normally held by the tension of the spring against the base of the slot when in use, a second sheet metal member having a body portion and spaced ears upstanding therefrom adapted to receive between them the ears and cylindrical portion of the first member and having openings adapted to align with the openings in the ears of the first member and a removable pivot pin passing through the ears of the two members, through the cylindrical portion of the first member and through the spring, the body portion of the first member being engageable with the projecting end of the spring to shift the same outwardly in the slot of the cylindrical portion whereby relative pivotal movement of the members out of a normal position is yieldingly resisted by the spring and the

spring acts to return the members to normal position and said members being separable without disturbing the spring or releasing the tension thereof.

5. A hinge comprising a member having an integral cylindrical portion along its inner edge, said cylindrical portion having intermediate its ends a circumferentially extending slot, a pair of springs enclosed by 10 and retained within the cylindrical member, said springs having their outer ends fixed to said member and their inner ends projecting through said slot and normally held by the tension of the springs against an end 15 of the slot when the elements of the hinge are separated, a second member having spaced upstanding ears adapted to receive between them the cylindrical portion of the first member and having openings adapted 20 to be aligned with the cylinder, and a removable pivot pin passing through said ears, through the cylinder and through the springs within the cylinder, said second member having a portion engageable with 25 the projecting end of the spring to shift the same in the slot upon a relative pivotal movement of the hinge members in one direction whereby the springs act to yieldingly oppose pivotal movement of the hinge 30 members from a normal position and to return the hinge members to normal position, said hinge members being detachable one from the other without disturbing the spring or releasing the tension thereof.
- 35 6. A hinge comprising two separable members, each having extending parts with

openings which are adapted to align, a removable pivot pin extending through said openings, a pair of coil springs through which the pintle extends, each coil spring 40 having its opposite ends bearing against the respective hinge members, and means integral with one of the hinge members for partially incasing the springs and for limiting the unwinding movement of the 45 springs when the hinge members are separated.

7. A hinge having two leaves, each having ears extending therefrom with pivot pin openings therethrough, a removable pivot 50 pin arranged to extend through the openings in the ears, the ears of one leaf being arranged to be received between the ears of the second leaf, a spring retainer fixedly connected to the first leaf, a helical spring 55 in the retainer being held therein against any substantial radial movement relative to the axis of the pin openings or along said axis, one end of the spring being arranged to exert pressure on the second leaf when 60 the leaves are connected by the pin and the leaves are in their normal swinging positions, and a fixed stop on the first leaf in the line of movement of the last mentioned end of the spring to prevent unwinding 65 thereof if the leaves are disconnected or if the leaves are moved beyond a predetermined limit in one direction.

In testimony whereof, I hereunto affix my signature.

CHARLES HABART.
